UNITED STATES PATENT OFFICE

HANS C. BEHR, OF SCARSDALE, NEW YORK

CENTRIFUGAL DRIER

Application filed August 3, 1928. Serial No. 297,294.

The object of this invention is to provide means for intermittently and automatically supplying to a centrifugal drier a measured quantity of the mixture of solids and liquid 5 which it is desired to treat.

To obtain capacity in any given apparatus the measuring chamber must be filled and emptied quickly, and the filling as in my present device is preferably effected by suction 10 during the operation of the drier. And its discharge from the measuring chamber to the drier is, for this reason, effected by either compressed air or by steam pressure.

The discharge of the dried solids is also 15 preferably performed automatically.

Another object of the invention is to assure the uniform distribution of the mixture on the screen of the drier so as to keep the rotating system in balance.

20 The invention also includes certain novel features of design as applied especially to the self-discharging type of drier already in use in a special construction of the baskets, and parts associated with it which include means 25 for applying fluid pressure to aid in dislodging the dried solids from the basket, and to thereafter clean its screen surface.

In the drawings accompanying this application, one practicable embodiment of the invention is shown by way of illustration, in 30 which drawings—

Figure 1 is a central sectional view of the apparatus embodying my invention.

Fig. 2 is a top view of the apparatus shown 35 in Figure 1.

Fig. 3 is a detail of a part of the inner surface of the basket shown in section in Figure 1.

Fig. 4 is a view partly in elevation and 40 partly in vertical section looking at Figs. 1 and 2 from the left-hand side.

Fig. 5 is an enlarged detail of the parts shown in Figure 1 for automatically timing and controlling the operation of the various 45 parts of the apparatus, and

Fig. 6 is a detail of a modification of the device for supplying fluid for freeing the solid material from the screen.

The material under treatment is fed by 50 intermittently delivered metered charges to a

rotating basket 10 by means of a continuously rotating distributor 11.

The illustrated form of basket comprises a solid outer wall 12 which is slightly larger at the top than at the bottom. The inner surface of this wall is provided with a series of channels 13 running from the bottom to the top, such channels being located between rows of ridges 14 so located that they are in effect a number of circumferential channels interrupted by the channels 13. Openings 15 are provided at the upper portion of the basket member 12. These openings 15 are preferably located out of direct line of the travel of the liquid up the passages 13, they are 65 shown as being located at the upper ends of the rows 14 circumferential ridges.

The screen 16 is disposed inwardly of the basket member 12 and lies against the thin edges of the ridge members 14.

The bottom of the basket comprises an outer cone 17 to which the basket member 12 is secured, and an inner cone 18, these cones being held together by a series of connecting ribs 19. The inner cone 18 is formed integrally with a plate 20 having a flat substantially horizontal portion which is bolted to and supported by the head 22 of the driving shaft 23, such shaft having fastened upon it a pulley 24 driven by means of a belt 25 from some suitable source of power.

An annular cover 26 is secured to an upper flange 27 formed on the basket member 12. In the underside of this annular cover 26 a ring 28 is secured for holding the upper edge 85 of the screen 16. The lower edge of the screen being held in place by the upper edge of the outer cone 17.

The shaft 23 is shown mounted in a sleeve or supporting member 29 which is carried by 90 ribs 30 preferably formed integrally with it and with the framing ring 31 which is bolted to the floor represented at 32. Ball bearings 33, 34 are mounted at the top and bottom of the sleeve 29, and are mounted upon suitable 95 seats formed on the shaft 23. A separating or spacing sleeve 35 may be placed around the shaft 23 for engaging the inner races of the two bearings and for keeping them a proper distance apart. Since the shafting

and bearing mountings form no part of this present invention, the details of their construction will not be specially enumerated.

Pipes 36 discharge fluid at the appropriate time outwardly of the screen 16 for the purpose of removing the dried material and for cleaning the screen surface. The connection between these pipes 36 and the controller 37, which is a combined exhaust and compression device, will be described later.

10 The material for treatment is supplied from a mixing chamber 38, the lower portion only being illustrated, in which lower portion a rotary stirrer 39 is illustrated. The blades of this stirrer are free from contact with the bottom walls of the mixing chamber.

15 The measuring chamber 40 is alternately subjected to a vacuum for assuring its rapid filling, and also to pressure for assuring its rapid evacuation by means of a pipe 41 connecting it with the controller 37.

20 The charge of material is preferably drawn off from the mixing chamber 38 through an opening 42 communicating with the upper portion of the measuring chamber. This side opening 42 is of some height above the bottom of the mixing chamber so that any solid, heavy, foreign matter which may collect at the bottom of the chamber 38 will now be prevented from entering the measuring chamber.

25 For preventing light, floating material entering, a screen 43 is shown located over the opening 42. The opening 42 is closed from the inside by means of a flap valve 44. 30 The seat of this valve is formed by a plate 45. The valve is pivoted to a lever 46 which lever is pivoted to a bracket 47. The lever is somewhat in the nature of a bell crank lever and is provided at its upper end with a counterweight 48 for holding the valve 47 to its seat. For the purpose of limiting the range 35 of opening movement of the valve 44, and for keeping it permanently closed if desired, a set screw 49 is provided.

40 The feed tube 50 for the distributor 11 constitutes the lower portion of the measuring chamber. This feed tube is supported by members 51 of the main frame of the machine, and is shown having a flexible or elastic connection 52 with the spout tube of the lower part of the chamber 40. The lower end 53 of the feed tube is shown conical, and is shown closed by means of a downwardly opening conical valve 54 which is reversely conical.

45 The valve stem 55 is shown guided by a support 56 and between which and a head 57 on the valve stem is mounted a compression spring 58. Such spring is of sufficient strength to hold the natural weight of the predetermined charge, but capable of yielding and permitting the valve to open and allow the discharge of the measured charge when the predetermined pressure acts on the surface of the charge.

50 A float valve 59 is located at the upper

portion of the measuring chamber for closing off communication between the pipe 41 upon the charge reaching the predetermined height. The valve 60 associated with this float will shut the chamber 40 against suction but will readily yield when pressure is supplied through the pipe 41.

70 The feed tube 50 constitutes the mounting or support for the rotary distributor 11. In the illustration, the inner race rings of a pair of ball bearings 61 are shown mounted upon the outer portion of the tube 50, these rings being shown spaced by means of a suitable spaced tube 62. The outer rings of the bearings are mounted in an upwardly extending sleeve 63 formed in the present instance integrally with the body portion of the distributor 11. This sleeve 63 is shown carrying a pulley 64 over which runs a belt 65 driven from some suitable source of power.

75 Upon the application of pressure either compressed air or steam as the exigencies in carrying out the process may demand, the material in the measuring chamber 40 is caused to press the valve 54, whereupon it is immediately received at the inner edge of the rotating equalizing cone 66, the rotation of which is imparted to the material by frictional contact. The centrifugal force thus imparted to the material, acting against the 80 conical surface of cone 66, will cause said material to assume a truly centered surface about the axis of rotation, so that it will be delivered in a sheet of uniform thickness at the outer edge of the likewise truly centered cone 66. The outer flange 67 of cone 66 is bolted against distance pieces 69 on the lower face of the flange 68, which flange is integral with sleeve 63.

85 The charge as it is driven out centrifugally is equalized, so far as circumferential distribution is concerned, by the mechanism just described. But for the purpose of still further distributing this charge equally over the surface of the screen 16 carried by the basket 12, 90 a double outer cone 70, 700 is provided. These cone members present a V-shaped deflector for the material as it rushes outwardly, and some of the material goes toward the upper part of the basket and some toward the lower part. These cones 70, 700 are preferably formed integrally and are carried by means of an inwardly directed flange 71 which enters slots formed in the distance pieces.

95 The timing of the operating cycle of alternately filling and discharging chamber 40, of admitting washwater to the machine and diverting the diluted liquid to a different receptacle from that for the pure liquid and of admitting pressure fluid to aid in dislodging the dried solids and cleaning the screen surface is effected by the controlling apparatus mounted at the left of chamber 40 (Fig. 1), and is more clearly shown on an enlarged 100 scale in Fig. 5.

Referring to such Fig. 5, it will be seen that the measuring chamber 40 through the fitting 70 is in permanent communication with a channel 72 in the valve chamber 73, the communicating bent pipe 41 being made of flexible material to permit moderate relative displacement between the parts 40 and 73. In the bottom of the channel 72 is fixed the small vacuum chamber 74, communicating through a lateral opening 75 and pipe 76 with a suitable partial vacuum source. The upper opening 77 of chamber 74 is intermittently closed by the valve 78, which is held to its seat by the pressure of spring 79. When the valve 78 is lifted off its seat vacuum is established in channel 72 and, by its connection 41, in the chamber 40, so that the flap valve 44 is forced open and the mixture to be treated enters to fill chamber 40, as previously explained.

Above the lower part of the channel 72 in valve chamber 73 is provided the pressure space 80, and connecting such spaces is the valve port 81, covered by the pressure admission valve 82 held to its seat by the pressure in space 80 and that of the spring 83. When the valve 82 is lifted, pressure is admitted to space 72 and passage 71, onto the top of the mixture in chamber 40, thereby forcing open outlet valve 54 and rapidly discharging the chamber 40. The mixture charge flowing down into the rotating conical basin or rotating equalizing cone 66 has rotation imparted to it by frictional contact, so that it flows outwardly and upwardly. Air or steam pressure is supplied to the space 80 through a pipe 84 from some convenient source.

At the end of the valve chamber 72, adjacent chamber 40, is the water chamber 85 supplied with water under pressure through pipe 86, and communicating through a port 87 with a chamber 88 beneath, intermittently closed off from chamber 85 by a valve 89, under pressure of water and that of a spring 90. The lifting of the valve 89 admits water to the chamber 88 and out through a pipe 91 and a spray 92 onto the material being treated on the screen 16.

Forming an extension of the outer end of the valve chamber 73 and supplied with fluid under pressure through a pipe 93 is another fluid pressure space 94, which in some cases may be simply an extension of the space 80, thus omitting the partition 95. Below the space 94 and communicating with it through a valve port 96 is a space 97. The port 96 is intermittently closed by a valve 99 under the pressure in the space 94 and that of a spring 98, but the lifting of this valve admits fluid pressure from the space 94 through port 96 and through the pipe line 100, 101, 102, 103 and by an expanding chamber 104 forces the plunger 105 with packing 106 against the lower end of the shaft 23, thereby mak-

ing a fluid tight connection. Continuing, the pressure fluid passes through the duct system 107, 108, 109, 110 and 36 into the space between basket 19 and screen 16. Instead of the fluid tight connection through plunger 105 shown in Figure 1, the arrangement shown in Fig. 6 with injection nozzle 111 and conical mouth 112 at the bottom of duct 107 may be used.

The opening of each of the valves 78, 82, 75 89 and 97 is accomplished through the lifting rods 113, 114, 115 and 116 actuated respectively by cams 117, 118, 119 and 120 fixed on a cam shaft 121 mounted in the bearings 122 and 123, and rotated from some convenient source of power, for instance a pulley 124. These cams are adjusted circumferentially to cause lifting of each of the valves in proper succession and at the proper time intervals required for the series 80 of functions of charging, purging, washing and discharging, and such adjustment is made variable to suit conditions, as by the set screws 125 in the hubs 126 of the said cams.

The cams act on the lifting rods generally through rollers 127 mounted in slots in the blocks 128, the rods being adjustably screwed with their lower ends into the tops of the blocks. The blocks 128 are guided vertically 95 in suitable holes in the guide bar 129. The upper ends of rods are guided in the bores of the bonnets 130, 131 and 132 fitted to the lower face of valve chamber 73, which bonnets have stuffing boxes at their lower ends. The rod 113 is guided in a stuffing box at the lower end of the vacuum chamber 74.

With automatically started and stopped centrifugal driers of the type described the timing of the various operations must necessarily be kept in phase with the speed variations of the driers, and hence the rotation of the cam shaft 121 must be in fixed relation with the movements of whatever devices are employed for controlling the speed 105 variations of the said drier. To accomplish this the rotation of the cam shaft 121 may be employed to control the movements of such device by electrical, hydraulic or other known methods.

A bracket member 164 is carried by the lower end of the sleeve housing 29. The lower portion of this member is chamfered out and closed by means of a plate 165. Mounted in the frame 164 is the loosely fitted 110 centrally bored plunger 105 above described.

The rotation of the mixture distributing system, independently of and at a different rate from that of the intermittent or widely varying rotation of the basket 10 enables 125 equalization and uniform distribution of the mixture circumferentially over the screen 16, which distribution would not be uniform with said system rotating at too slow a rate as in unison with basket 10 during the charg- 130

ing period, because then the centrifugal force at the central equalizing basin 66 would not be sufficient to effect a satisfactory degree of circumferential equalization of the charge.

5 With a screen of considerable depth like that of Figure 1 and with the charge received on the screen only at a single narrow zone, or as in the ordinary centrifugal driers, which are generally charged on a closed bottom, 10 high speed during charging would cause so quick an escape of the liquid from the mixture that the latter would not remain sufficiently fluid to distribute itself vertically to any considerable extent.

15 An advantage of the independently rotated distributor is that its speed may be adjusted to give the best results in equalized distribution for various kinds of mixtures. Also, with a distributor rotating at a different rate from that of the basket, such difference in rotation affords an additional means for correcting any imperfection of circumferential equalization due to possible incomplete equalization within the distributor.

25 Rigid with the inner edge of the base 135 of the curb 136 is the inner cylindrical shell 137, and between this and the curb 136 is the shell 138, leaving between the latter and the curb the pure liquid basin 139 and between 30 the shells 137 and 138 the dilute liquid basin 140. The upper end of the shell 137 is a little below the level of the holes 15 in the basket 10 and an annular conical deflector 141 in its lowest position rests on the top of the shell 137, and is rigid with a downwardly extending ring 142 fitting loosely inside the top of the shell 138 and of sufficient length to remain within the shell when the deflector is in its extreme raised position with its inner 40 edge a little above the circle of holes 15 in the basket 10, as indicated in broken lines. When the deflector 141 is in its lowest position the liquid issuing from the holes 15 is projected against the inside of the curb 136 and flows down into the basin 139, from 45 which it is drawn off through the outlet 143. When the deflector 141 is in its highest position, as indicated in broken lines, the liquid from the holes 15 strikes its underside and is thereby diverted down into the basin 140 and drawn off through the outlet 144.

50 For the purpose of raising the deflector 141, there are fixed to it four lugs 145 by which it is suspended through rods 146 furnished with jaws 147, pivoted to the ends of levers 148, 149, 150, 151. These levers are secured with their hubs on the ends of two parallel rockshafts, which are carried in the open top bearings 152. The lever 150 has 55 rigid with it an opposite arm 153, the end of which is loosely pivoted to an arm 155 opposite to and rigid with lever 151, so that the ends of levers 150 and 151 must rise and fall together by equal amounts in adjusting the 60 deflector 141. The other levers 148 and 149

will also move in unison with the levers 150 and 151 by the same amount, since they are all rigidly connected to the same shafts. Movement is imparted to the system of levers by the rotating cam 156, mounted on the cam shaft 157, acting downwardly on a roller 158 journalled in an arm 159 opposite to and rigid with lever 148.

70 The admission of pressure fluid through the system of ducts 160, 36, etc. to the space between the basket 10 and the screen 16 previously described, is effected by a stationary fluid pressure conveying system intermittently and automatically brought into service to inject fluid under moderate pressure into 75 said first named system.

80 The operation of the apparatus and of the process carried out thereby are as follows: The chamber 40 is filled with a charge of the mixture to be separated during the time occupied by the purging, washing, drying and discharging periods of the basket 10. The float 59 closes the valve 60 and the partial vacuum is compressed to atmosphere by the mixture at the end of the inflow, so that flap valve 46 is closed by the weight 48. Vacuum valve 78 is also permitted to close by rotation of its cam 117. Valve 82 is lifted by cam 118 and allows pressure to act through space 72 and pipe bend 41, which pressure, 85 forcing down the float valve 59 and acting on the surface of the mixture in the chamber 40, forces open the outlet valve 54 and expels the contents of the chamber. The mixture is thus made to flow down into the rotating equalizing basin 66, which, in the manner previously explained, expels the mixture in a sheet of uniform thickness into the space between discs 67 and 68, where the ribs 69 further accelerate it and cause it to flow outwardly and to be split by the flange 71 into two streams, one flowing upwardly over cone 70 and the other downwardly over cone 70, escaping further out over the edges of said cones in two zonal streams, which thus deposit the mixture circumferentially uniformly onto the screen 16. During such deposition basket 10 revolves at a very slow rate, just sufficient to expel some of the liquid so as to keep the mixture from flowing down by 90 gravity over cone 70 and out, but not so fast that enough liquid will be extracted to prevent the mixture from distributing itself vertically to a satisfactory degree over the surface of the screen 16. During such deposition basket 10 revolves at a very slow rate, just sufficient to expel some of the liquid so as to keep the mixture from flowing down by gravity over cone 70 and out, but not so fast that enough liquid will be extracted to prevent the mixture from distributing itself vertically to a satisfactory degree over the surface of the screen 16. When charging 95 has been thus completed, the basket 10 is accelerated up to full speed according to methods and by devices already in use. The liquid expelled through screen 16 during the period of purging flows upwardly through the channels 13 and out through the holes 15 in the basket 10, shooting out above the deflector 141 against the inside of the curb 78 to be caught in a basin 137 and led away 100 through the outlet 110.

105 For the purpose of raising the deflector 141, there are fixed to it four lugs 145 by which it is suspended through rods 146 furnished with jaws 147, pivoted to the ends of levers 148, 149, 150, 151. These levers are secured with their hubs on the ends of two parallel rockshafts, which are carried in the open top bearings 152. The lever 150 has 110 rigid with it an opposite arm 153, the end of which is loosely pivoted to an arm 155 opposite to and rigid with lever 151, so that the ends of levers 150 and 151 must rise and fall together by equal amounts in adjusting the 115 deflector 141. The other levers 148 and 149

After a period found to be sufficient for a suitable degree of purging from pure liquid, a further elimination of liquid adhering to the solid grains is usually obtained by spraying with water. Such a spray is here caused at the proper time by the suitably adjusted cam 120 lifting the valve 89, so that water flowing through the pipe 91 and the spray nozzle 92 is sprayed onto the material left on the screen, diluting and washing out therefrom the remaining viscous liquid, the dilution like the pure liquid being forced through the screen, then up through channels 13 and out through the holes 15 and against the underside of the conical deflector 108, which has been previously raised by the rotation of the cam 126 to the position indicated in broken lines in Figure 1, and which now deflects the solution down into the basin 107 to be drawn off through the outlet 111. The period of washing having been completed through the closing of valve 89, and a short period required for centrifugal drying of the solids, the basket 10 is slowed down, preferably by automatic means, and when a sufficiently slow speed or entire stoppage has been attained the dried solids are aided in dropping off the screen by pressure fluid admitted behind said screen by the opening of the valve 99 as previously described. The measuring chamber 40 having in the meantime been again filled, is ready to deliver a new charge to repeat the cycle of operations as described in the foregoing.

A number of centrifugal driers, arranged each with means to time and perform automatically the successive tasks constituting the cycle of operations hereinbefore described, may obviously have said means so connected that each of the said tasks, as for example that of charging, will not occur simultaneously, but in rotation at regulated intervals, thereby equalizing the demand on the power supply for operating the said number of driers.

It is to be understood that the centrifugal machine shown in the drawings, while being the preferred form, is illustrative of my invention and that changes may be made within the scope of the claims without departing from the spirit of the invention.

Having described my invention, I claim and desire to secure by Letters Patent:

1. The combination with a centrifugal drier, of means for intermittently charging such device, and comprising a supply storage reservoir, a metering chamber communicating with the supply storage reservoir through an inlet, a pressure operated valve controlling such inlet, a valved outlet at the lower portion of the metering chamber, a float controlled valved passage at the top of such chamber affording communication with two alternately and automatically supplied opposite fluid pressure sources, the mecha-

nism being constructed and adapted to cause the regular alternate filling and discharge of the metering chamber.

2. The combination with a centrifugal drier, of means for intermittently charging such device, and comprising a supply storage reservoir, a metering chamber communicating with the supply storage reservoir through an inlet, a pressure operated valve controlling such inlet, the metering chamber being formed with a tubular downward extension, a valved outlet at the lower end of such extension, a float controlled valved passage at the top of such chamber affording communication with two alternately and automatically supplied opposite fluid pressure sources, the mechanism being constructed and adapted to cause the regular alternate filling and discharge of the metering chamber.

3. In a centrifugal drier for separating liquid from solid material, the combination with a basket adapted to discharge the liquid separated within it at a single zone, of a fixed double concentric receiver for liquid surrounding the basket, a deflecting device, and means for automatically and intermittently raising and lowering such device for directing separated liquid alternately to the receivers.

4. In a centrifugal drier for separating liquid from solid material, the combination with a basket adapted to discharge the liquid separated within it at a single zone, of a fixed double concentric receiver for liquid surrounding the basket, a conical deflecting ring normally directing separated liquid to the outer of the receivers, and means for automatically and intermittently lifting such ring to its upper position for directing the liquid to the inner of the receivers.

5. In a centrifugal drier for separating liquid from solid material, the combination with a basket adapted to discharge the liquid separated within it at a single zone, means for spraying washing fluid against the material carried by the basket, a fixed double concentric receiver for liquid surrounding the basket, a conical deflecting ring, and means for automatically and intermittently lifting such ring to its upper position for deflecting dilute liquid to the inner one of the concentric receivers, and timed to function in proper relation to the application of the spray.

6. In a centrifugal drier, the combination with supply means including a downwardly directed spout, a distributor located below such spout and rotating relatively thereto, such distributing means comprising a substantially flat portion at the point of discharge of the spout, an outwardly flared conical chamber leading away from such flat portion, and a pair of outwardly flared cones

- beyond such flared chamber for separating the discharge into two zones.
7. In a centrifugal drier, the combination with supply means including a downwardly directed spout, a distributor located below such spout and rotating relatively thereto, such distributing means comprising a substantially flat portion at the point of discharge of the spout, an outwardly flared conical member rigid with and leading away from such flat portion, and a pair of outwardly flared cones beyond such flared chamber for separating the discharge into two zones.
8. In a centrifugal drier, the combination with supply means including a downwardly directed spout, a distributor located below such spout and rotating relatively thereto, such distributing means comprising a substantially flat portion at the point of discharge of the spout, an outwardly flared conical chamber leading away from such flat portion, a pair of outwardly flared cones beyond such flared chamber for separating the discharge into two zones, and a basket adapted to rotate at a different speed from the speed of the distributor and located in position for receiving the distributed discharged material.
9. In combination with a centrifugal drier, a metering chamber, a supply storage having an inlet into such chamber, such chamber having a spring controlled valve at its discharge capable of yielding upon the combined pressure of the weight of the charge augmented by the pressure fluid upon its surface, there being an opening in the upper part of the chamber, means for alternately exposing the chamber through such opening to reduced pressure and to increased pressure, a valve for closing such opening against suction, and a float for closing such valve upon the rise of the material in the chamber to a predetermined level, the mechanism being constructed, adapted and timed to cause the regular alternate filling and discharge of the metering chamber.
10. In a centrifugal drier, the combination with supply means including a downwardly directed spout, a distributor located below such spout and rotating relatively thereto, such distributing means comprising a substantially flat portion at the point of discharge of the spout, an outwardly flared conical member rigid with and leading away from such flat portion, a pair of outwardly flared cones beyond such flared chamber for separating the discharge into two zones, and a basket adapted to rotate at a different speed from the speed of the distributor and located in position for receiving the distributed discharged material.
11. The combination with a storage chamber for a centrifugal drier, having a curved trough shaped portion at the bottom, of a

stirrer in the form of a paddle wheel located in such trough but clearing its walls, a metering chamber having an opening communicating with the storage reservoir above the axis of rotation of the stirring device, a valve for closing the opening constructed and adapted to open upon reduction of pressure within the metering chamber and close upon positive pressure therein, the chamber having a port in its upper part, a float valve located in the upper part of the chamber and carrying a valve for pressure against such port, such metering chamber having a conically formed bottom extending into a tubular formation, the latter having at its bottom a conical valve seat, a conical valve located upon such seat and opening outwardly, and means for closing such valve, such means being normally strong enough to sustain the weight of the metered charge, and means for alternately and in timed sequence connecting the port at the upper portion of the metering chamber with low pressure and with high pressure.

12. The combination with a storage chamber for a centrifugal drier, having a curved trough shaped portion at the bottom, of a stirrer in the form of a paddle wheel located in such trough but clearing its walls, a metering chamber having an opening communicating with the storage reservoir above the axis of rotation of the stirring device, there being a screen for covering this opening, a valve for closing the opening constructed and adapted to open upon reduction of pressure within the metering chamber and close upon positive pressure therein, the chamber having a port in its upper part, a float valve located in the upper part of the chamber and carrying a valve for pressure against such port, such metering chamber having a conically formed bottom extending into a tubular formation, the latter having at its bottom a conical valve seat, a conical valve located upon such seat and opening outwardly, and a spring for closing such valve, such spring being normally strong enough to sustain the weight of the metered charge, and means for alternately and in timed sequence connecting the port at the upper portion of the metering chamber with low pressure and with high pressure.

13. The combination with a storage chamber for a centrifugal drier, of a metering chamber communicating with the storage chamber, means for causing the regular alternate filling and discharge of the metering chamber, a basket having solid walls except for a row of holes near one end for discharging the liquid in a single zone, the inner surface of the basket being formed with a screen support having channels leading toward the row of discharge holes, means operable in timed sequence with the discharging of the metering chamber for intermittently rotating the basket, a continuously rotating distribu-

- tor within the basket and below the discharge point of the metering chamber, the basket being adapted to rotate at a different speed from the speed of the distributor and located in position for receiving the distributed discharged material, means for spraying water against the material carried by the basket, a fixed double concentric receiver for liquid surrounding the basket, a conical deflecting ring, means for automatically and intermittently lifting such ring to its upper position for deflecting liquid to the inner one of the concentric receivers, and timed to function in proper relation to the application of the spray. 15. The combination with a storage chamber for a centrifugal drier, of a metering chamber communicating with the storage chamber means for causing the regular alternate filling and discharge of the metering chamber, a basket having solid walls except for a row of holes near one end for discharging the liquid in a single zone, the inner surface of the basket being formed with a screen support having channels sloping outwardly toward the row of discharge holes, means operable in timed sequence with the discharging of the metering chamber for intermittently rotating the basket, a continuously rotating distributor within the basket and below the discharge point of the metering chamber, the basket being adapted to rotate at a different speed from the speed of the distributor and located in position for receiving the distributed discharged material, means for spraying water against the material carried by the basket, a fixed double concentric receiver for liquid surrounding the basket, a conical deflecting ring, means for automatically and intermittently lifting such ring to its upper position for deflecting liquid to the inner one of the concentric receivers, and means timed to admit fluid under pressure between the basket and the screen for freeing the solid material from the screen. 16. The combination with a storage chamber for a centrifugal drier, of a metering chamber communicating with the storage chamber means for causing the regular alternate filling and discharge of the metering chamber, a basket having solid walls except for a row of holes near one end for discharging the liquid in a single zone, the inner surface of the basket being formed with a screen support having channels sloping outwardly toward the row of discharge holes, means operable in timed sequence with the discharging of the metering chamber for intermittently rotating the basket, a continuously rotating distributor within the basket and below the discharge point of the metering chamber, the basket being adapted to rotate at a different speed from the speed of the distributor and located in position for receiving the distributed discharged material, a fixed double concentric receiver for liquid surrounding the basket, a conical deflecting ring, means for automatically and intermittently lifting such ring to its upper position for deflecting liquid to the inner one of the concentric receivers, and means timed to admit fluid under pressure between the basket and the screen for freeing the solid material from the screen. 17. In a centrifugal drier, the combination with a basket, a screen carried by the basket, there being passages provided between the screen and basket, and means for intermittently rotating the basket, of means timed for admitting fluid under pressure to such passages upon the cessation of the rotation of the basket. 18. In a centrifugal drier, the combination with a basket, a screen carried by the basket, there being passages provided between the screen and basket, and means for intermittently rotating the basket at a speed sufficiently high to centrifugally urge the material outwardly against the screen and slowing down the speed to relieve such outward centrifugal urge, of means timed for admitting fluid under pressure to such passages upon the slowing down of the speed of the rotation of the basket. 19. The combination with a storage chamber for a centrifugal drier, of a basket having solid walls except for a row of holes near one end for discharging the liquid in a single zone, the inner surface of the basket being formed with a screen support having chan-

nels sloping outwardly toward the row of discharge holes, means for intermittently rotating the basket, a continuously rotating distributor within the basket, the basket being adapted to rotate at a different speed from the speed of the distributor and located in position for receiving the distributed discharged material, means for spraying water against the material carried by the basket, a fixed double concentric receiver for liquid surrounding the basket, a conical deflecting ring, means for automatically and intermittently lifting such ring to its upper position for deflecting dilute liquid to the inner one of the concentric receivers, and timed to function in proper relation to the application of the spray.

20. The combination with a storage chamber for a centrifugal drier, of a basket having solid walls except for a row of holes near one end for discharging the liquid in a single zone, the inner surface of the basket being formed with a screen support having channels sloping outwardly toward the row of discharge holes, means for intermittently rotating the basket, a continuously rotating distributor within the basket, the basket being adapted to rotate at a different speed from the speed of the distributor and located in position for receiving the distributed discharged material, means for spraying water against the material carried by the basket, a fixed double concentric receiver for liquid surrounding the basket, a conical deflecting ring, means for automatically and intermittently lifting such ring to its upper position for deflecting dilute liquid to the inner one of the concentric receivers, and timed to function in proper relation to the application of the spray, and means timed to thereafter admit fluid under pressure between the basket and the screen for freeing the solid material from the screen.

21. The combination with a storage chamber for a centrifugal drier, of a basket having solid walls except for a row of holes near one end for discharging the liquid in a single zone, the inner surface of the basket being formed with a screen support having channels sloping outwardly toward the row of discharge holes, means for intermittently rotating the basket, a continuously rotating distributor within the basket, the basket being adapted to rotate at a different speed from the speed of the distributor and located in position for receiving the distributed discharged material, a fixed double concentric receiver for liquid surrounding the basket, a conical deflecting ring, means for automatically and intermittently lifting such ring to its upper position for deflecting liquid to the inner one of the concentric receivers, and means timed to admit fluid under pressure between the basket and the screen for freeing the solid material from the screen.

22. In a centrifugal drier, the combination with a basket, a screen carried by the basket, there being passages provided between the screen and basket, a shaft supporting the basket, and means for intermittently rotating the shaft, of means timed for admitting fluid under pressure to such passages upon the cessation of the rotation of the basket and comprising a fluid conduit leading from a source of supply to such passages, the shaft being formed with a bore constituting a part of the fluid conduit, an expansion chamber open to the pressure of fluid in the conduit, and a plunger having a bore constituting a part of the fluid conduit, controlled by the expansion chamber and constructed and adapted to engage the end of the shaft upon rise of pressure in the expansion chamber and complete the conduit and to be freed from the shaft end upon fall of pressure in such chamber.

Signed at New York, N. Y., this first day of August, 1928.
